UNITED STATES PATENT OFFICE.

HERMAN IHLENBURG, OF PHILADELPHIA, PENNSYLVANIA, ASSIGNOR TO
THE MACKELLAR, SMITHS & JORDAN COMPANY, OF SAME PLACE.

DESIGN FOR A FONT OF PRINTING-TYPE.

SPECIFICATION forming part of Design No. 18,736, dated November 13, 1888.

Application filed October 18, 1888. Serial No. 288,469. Term of patent 7 years.

To all whom it may concern:

Be it known that I, HERMAN IHLENBURG, a citizen of the United States, and a resident of Philadelphia, Pennsylvania, have invented 5 a new and original Design for a Font of Type, of which the following is a specification.

My design is clearly shown in the accompanying typographic impression, to which reference is made.

- ,o The font of type is termed "Fancy," and consists of ornamental, plain-line, unshaded letters, the letters A, B, G, J, L, O, Q, R, S, W, X, Y, and Z of the upper-case having portions terminating in a scroll. The terminations of the vertical lines of the remaining letters are flared or thickened, as fully shown. The letters of the upper-case are not of uniform depth, the letters A, B, D, E, G, I, K, L, M, N, O, S, U, V, W, X, and Z being 15 of one depth, while the remaining letters, C, F, H, J, N, P, Q, R, T, and Y, are of greater depth, the top of each of the upper-case letters, however, being on the same line, so as to impart an even appearance to the top of the

printed line. The bottoms of the letters, however, are not all in the same plane, the letters C, F, H, J, N, P, Q, R, T, and Y projecting below the others. The open letters C, U, and V of the upper-case type are ornamented by a central dot. 25

The peculiar characteristics of the upper-case types are preserved in the lower-case letters so far as is compatible with the changed form of the latter. 30

The top of each of the numerals is on the same line, while the numerals 3, 4, 5, 7, and 9 project below the others. 35

I claim as my invention—

The design for a font of type, substantially as described and shown. 40

In testimony whereof I have signed my name to this specification in the presence of two subscribing witnesses.

HERMAN IHLENBURG.
